UNITED STATES PATENT OFFICE.

WILLIAM S. WEEDON, OF SCHENECTADY, NEW YORK, ASSIGNOR TO GENERAL ELECTRIC COMPANY, A CORPORATION OF NEW YORK.

ELECTRIC-ARC LAMP.

No. 926,792.

Specification of Letters Patent.

Patented July 6, 1909.

Application filed March 12, 1904, Serial No. 197,832. Renewed April 7, 1906. Serial No. 310,475.

To all whom it may concern:

Be it known that I, WILLIAM S. WEEDON, a citizen of the United States, residing at Schenectady, county of Schenectady, State 5 of New York, have invented certain new and useful Improvements in Arc-Lamps, of which the following is a specification.

When arc light electrodes are formed of or contain large amounts of some material, such 10 as titanium carbid, the arcing end of the electrode may become more or less covered with a film or layer of material formed by the arc which is non-conducting when cold.

The object of my present invention is the 15 provision of novel and efficient means for starting an arc from such an electrode.

In carrying out my invention I provide means for starting an arc from the side of the electrode some distance from its arcing end 20 and then transferring the arc to the end of the electrode. With a negative electrode giving a flaming or luminous arc a non-consuming positive electrode may be employed. In the drawings forming a part of the present 25 specification I have shown my invention employed in connection with such an electrode.

The various features of novelty which characterize my invention are pointed out with particularity in the claims annexed to 30 and forming a part of this specification. For a better understanding of my invention, however, reference may be made to the accompanying drawings and description in which I have illustrated and described one 35 embodiment of it.

Of the drawings, Figure 1 is a view partly in elevation and partly diagrammatic illustrating an arc lamp equipped with my invention; Fig. 2 is a perspective view showing a 40 portion of the non-consuming electrode-carrier provided with my arc-starting device; Fig. 3 is an elevation showing a portion of the mechanism; Fig. 4 is a sectional elevation illustrating a detail; Fig. 5 is a view similar to Fig. 3 showing the parts in a different position; and Fig. 6 is a perspective view 45 similar to Fig. 2 showing a modified construction.

My invention may be advantageously employed in connection with the lamp shown 50 and described in an application for a patent on arc lamps filed jointly by Richard Fleming and Cromwell A. B. Halvorson, Jr., on the 16th day of Nov. 1903, the serial num-

ber of which is 181,332, though it is not 55 limited to use in connection with any particular form of lamp.

The mechanism shown in Fig. 1 is substantially the same as that shown in the application above noted except as it is modified 60 by the addition of my present invention.

Referring to the drawings, 1 represents a platform forming a part of the frame work of the lamp. A conical member 2, forming a part of the draft tube or chimney of the 65 lamp, has its upper and smaller end secured to and insulated from the under side of the platform 1 in any suitable manner. A metal shaft 3 is journaled in diametrically opposed openings formed for the purpose in the 70 conical member 2 near its lower end. For convenience in removing the shaft the portions which pass through the wall of the member 2 may be in the form of screws 4 which are detachably secured to the main 75 portion of the shaft. A sector shaped part or member 5, which may be integral with the shaft 3, extends at right angles therefrom near one of its ends. The lower and wider end of the part 5 carries at one side a pair of 80 transversely extending projections 6 and 7.

A block 8 formed of some material which is conducting and with which it is easy to form a good electrical contact is pivotally mounted between the extensions 6 and 7. 85 The block 8, which is preferably formed of carbon but may in some cases be formed of graphite, copper or other material, is roughly L-shaped in cross section, as is clearly shown in Fig. 4. The main portion 9 of the block 90 is normally substantially perpendicular to the member 5, being held in that position by the engagement of the downwardly extending portion 10 of the block with the lower end of the member 5. The under surface of 95 the portion 9 is substantially cylindrical about the shaft 3 as an axis. The lower part of the portion 10 is enlarged.

A lateral extension 7', from the projection 7, has detachably secured to its outer end a 100 suitably formed block or member 11 preferably formed of wrought copper. A screw 11' may be employed to secure the block 11 in place. Instead of relying upon simple contact for electrical connection between the 105 portions 2 and 3 and also between the portions 5 and 8, such contact may be better secured by the use of flexible connecting con-

ductors secured at their ends to said portions. The parts are so arranged and proportioned that when the mechanism is in the position shown in Figs. 3 and 1 block 11 is in line with the axis of the conical member 2. In the position of the apparatus shown in Fig. 1 the portion 10 of the block 8 appears somewhat to the left of, and the center of the portion 9 substantially in line with, the axis of the member 2. The member 5 and the blocks 8 and 11 may be regarded as forming the positive electrode of the lamp or the member 5 may be regarded as a frame in which are mounted the block 11 forming the main non-consuming positive electrode of the lamp, and the block 8 forming an auxiliary starting electrode.

A collar 12 which may be adjustably secured to the shaft 3 near one of its ends has secured to it one end of a bent crank arm 13. A portion of the arm 13 extends through an arc-shaped slot 13' formed for the purpose in the wall of the conical member 2. The outer end of the arm 13 is link-connected to a U-shaped armature 14 which with its co-operating winding 15 is mounted above the platform 1.

To the under side of the armature 14 is secured one end of the pawl 16 of a clutch 16', the yoke of which surrounds a vertical tubular member 17. The lower end of the tubular member 17, which slides on a suitably supported guide rod 18, carries an arm 19 at the outer end of which is formed a socket in which the negative consuming electrode 20 is held. The parts are so proportioned and arranged that the electrode 20 is in line with the axis of the conical member 2.

The electrode 20 is preferably formed out of, or contains some substance giving a flaming or luminous arc such as titanium carbide. When the electrode is formed of or contains titanium carbide it should preferably be coated with metal such as copper.

When the windings 15 are energized in the manner hereinafter described the armature 14 will be raised and the clutch 16' will engage the member 17 and move the electrode 20 into engagement with the under side of the portion 9 of the block 8 which will then be oscillated about the shaft 3 into the position shown in Fig. 5 by the link-connection between it and the armature. The engagement of the upper end of the electrode with the under side of the portion 9 of the block 8 will tilt the enlarged lower part of the portion 10 into engagement with the side of the electrode as shown in Fig. 4.

When the clutch 16' is in the position shown in Fig. 1 its yoke rests upon the upper surface of a stop 21 adjustably mounted on a rod 22 extending upward from the platform 1. Under these circumstances the member 17 is free to move through the

clutch 16'. The pawl 23 of a clutch 24 is normally held in engagement with the member 17 by the action of a spring 25, the upper end of which is secured to a cross part 26 which connects the rods 18 and 22. When the member 17 is raised the clutch 24 will move upward with it until the pawl 23 strikes the lower surface of the stop 21 after which the member 17 will move through the yoke of the clutch 24. In the position shown in Fig. 1 the pawl 23 rests against the upper side of a stop 27 also secured to the rod 22. In this position of the pawl 23, the member 17 is locked between the pawl and the yoke of the clutch 24 and is thereby prevented from moving downward.

The circuit arrangements of the lamp and its operation may be understood by reference to Fig. 1, in which 30 and 31 represent the lamp terminals. A conductor 32 connects the terminal 30 to the electrode 20. One terminal of the windings 15 is also connected to the terminal 30. The other terminal of the windings 15 is connected to a contact member 33 by a conductor 34. The contact member 33 is carried by an armature 35 pivotally mounted on a core 36 of an electro-magnet 37. When the electro-magnet 37 is de-energized the contact 33 is in engagement with a contact member 38 but when the electro-magnet 37 is energized the contacts are separated. The contact member 38 is connected by a conductor 39 to one terminal of a resistance conductor 40, the other end of which is connected to the terminal 31. A conductor 41 connects one terminal of a voltage coil 42 with the line 39, the other terminal of the voltage coil 42 being connected to the conductor 34. A conductor 43 connects the lamp terminal 31 with one end of the winding of the electro-magnet 37. The other end of the winding of the magnet 37 is in electrical connection with the conical member 2 and thereby with the member 5 and blocks 8 and 11. The pivoted armature 44 co-operating with the voltage coil 42 carries a contact 45 which is normally separated from but is adapted under some circumstance to engage the contact 46 carried by the core of the magnet. A conductor 47 connects the contact 45 to the line 43. A conductor 48 connects the contact 46 with the lower terminal of the winding of the electro-magnet 37.

The out-of-service condition of the lamp is shown in Fig. 1. When the lamp terminals are connected to a suitable source, current will begin to flow from terminal 31, through resistance 40, conductor 39, contacts 38, 33, conductor 34, through coils 15, to terminal 30. The passage of current through the winding 15 will cause the armature 14 to be raised. This will move the electrode 20 into contact with the under side of the portion 9 of the block 8, which will then be oscillated

into the position shown in Fig. 5. The parts are usually so proportioned that the electrode 20 will clear the portion 10 of the block 8 as it moves upward. When the 5 upper end of the electrode 20 engages the under side of the portion 9 of the block 8 the block 8 will be tilted and the lower and large part of the portion 10 will be forced against the side of the electrode 20, as shown in 10 Fig. 4, at a point far enough below its upper end to insure freedom from the presence of non-conducting material formed by the arc. Current will then begin to flow between the electrode 20 and the portion 10 through a 15 circuit which starting from terminal 31 includes conductor 43, coil 37, block 8, portion 10 of that lock, electrode 20, and conductor 32 to terminal 30. The passage of current through the winding of the electro-magnet 20 37 will cause the armature 36 to be oscillated and thereby separate the contacts 33 and 38. When this occurs the winding 15 will be 25 de-energized, the electrode 20 will begin to descend, and the block 8 start back to the position shown in Fig. 3.

As the block 8 and the electrode 20 separate, an arc will usually be drawn between the portion 10 and the side of the electrode which will first be transferred from the portion 10 to the portion 9 of the block 8 and 30 then to the block 11 as the movement of separation continues. The heat produced by this arc will soon cause the end of the electrode 20 to become conducting after 35 which the arc will extend from the upper end of the electrode. In some cases sufficiently good contact may be established between the end of the electrode 20 and the portion 9 to cause the arc to be formed initially between 40 the end of the electrode and the portion 9. The downward movement of the electrode 20 and thereby the arc length will be limited by the engagement of the pawl 23 with the stop 27.

45 The voltage coil 42 is so proportioned that for ordinary arc lengths the current passing through its winding will be insufficient to attract the armature 44. When, however, the voltage of the arc increases to a predetermined maximum the current passing through 50 the winding 42 will cause the armature 44 to be attracted and thereby bring the contact 46 into engagement with the contact 45. This throws a low resistance shunt comprising 55 the conductor 47, contacts 45 and 46 and conductor 48 about the winding of the electro-magnet 37, whereupon the contact member 33 will move into engagement with the contact member 38 and close the circuit 60 through the winding 15. The electrode 20 will then be again moved into engagement with the under side of the portion 9 of the block 8, after which the arc will again be struck in the manner hereinbefore described. 65 The feeding operation will be repeated when-

ever the voltage of the arc rises above a predetermined maximum thus compensating for the consumption of the electrode 20.

It will be readily understood that when each feeding action takes place the clutch 24 70 will move with the tubular member 17 until the pawl 23 strikes the under side of the stop 21 after which the member 17 will be moved through the yoke of the pawl 24 an amount equal to the length of the electrode consumed 75 since the previous feeding operation.

With the construction employed it will be observed that the lower end of the portion 10 of the block 8 is positively forced against the side of the electrode 20 with a pressure proportional to the lifting action of the winding 15 on the armature 14. This can be adjusted to obtain any desired amount of pressure. As the block 8 can be made quite massive, and as the arc extends from it only 85 for a short time during each feeding interval, its consumption will be very slow. With the construction employed, however, renewal of the block can take place whenever necessary.

As the under surface of the portion 9 of 90 the block 8 is substantially cylindrical about the axis of oscillation of the member 5, there is no tendency to a wedging or locking action between the electrode 20 and the block 8 when they move together. It will also be 95 readily observed that by this arrangement the same length of arc will be drawn at all times during the feeding of the lamp. Thus, if the electrode 20 has been consumed but little, when the lamp feeds, its upper end 100 will come into contact with the portion 9 of the block 8 at a point near the extension 7; whereas if the electrode 20 has been consumed to a greater extent the engagement between the electrode 20 and the portion 9 105 takes place at a point nearer to the extension 6 than in the previous case. In both cases, however, the length of the arc obtained is the same, since the under surface of the portion 9 is substantially cylindrical 110 about the axis of oscillation of the member 5 and the electrode 20 will fall the same distance in the two cases, said distance being determined as hereinbefore described.

When the block 8 is formed of carbon or 115 similar material of the same general character, impingement of the end of the electrode 20 against the under side of the block 8 can frequently be relied upon to start the flow of current between the block 8 and the 120 electrode 20, even though the electrode tip be covered with a film or layer of material which is practically non-conducting when cold. This result may perhaps be due to particles or granules separated from the 125 block 8 of carbon by the impingement entering into minute cracks or fissures in the films or layers of non-conducting material covering the end of the electrode; or it may be due to other causes. Owing to this fact the 130

use of the portion 10 of the block 8 under some circumstances becomes unnecessary and the portion may be dispensed with. In Fig. 6 I have shown a construction in which 5 a block 8', substantially like the portion 9 of the block 8 shown in the other view of the drawings, is rigidly secured between the extensions 6 and 7 of the member 5.

While in the foregoing description and the 10 accompanying drawings I have described and illustrated the best forms now known to me in which my invention may be embodied I do not consider that my invention in its broader aspects is limited to any particular form.

What I claim as new and desire to secure by Letters Patent of the United States, is:

1. In an arc lamp, the combination of a movable frame carrying a block of carbon 20 and a block of copper, a consuming electrode, and means actuating the frame and the consuming electrode for causing an arc to start between the consuming electrode and the carbon block and for maintaining it 25 between the consuming electrode and the copper block.

2. In an arc lamp, a pivoted block of carbon, an electrode, and means for causing one portion of said electrode to be impinged 30 against one portion of said block to turn the latter about its pivot and thereby force another portion of said block into contact with a different portion of said electrode.

3. In combination, an electrode, a pivotally mounted L-shaped block of carbon, and means for causing an engagement between one leg of the carbon block and the end of the electrode so as to oscillate the block upon its support and thereby the other leg of the 40 carbon block against the side of the electrode.

4. In an arc lamp, an electrode, a movable frame carrying a metal arcing portion and a non-metal arcing portion, means for moving 45 said non-metal arcing portion into line with said electrode to start an arc between the two and for thereafter moving said non-metal arcing portion out of line with said electrode and for moving the metal arcing 50 portion into line with said electrode whereby an arc is maintained between said electrode and the metal arcing portion.

5. In an arc lamp, an electrode, a movable frame or member provided with two surfaces from which an arc may extend, means for moving one of said surfaces into line 55 with said electrode in order that an arc may be started between said surface and the electrode and for thereafter moving the 60 other of said surfaces in line with said electrode in order that an arc may be maintained between said other surface and said electrode.

6. In an arc lamp, an electrode, a movable frame or member, a metal block carried

thereby, a second block also carried thereby, means for moving said second block into line with said electrode to start an arc between said second block and said electrode and for thereafter moving said frame to 70 bring said metal block into line with said electrode.

7. In combination, an electrode, a movable frame, a block of carbon and a block of copper carried thereby, means for causing 75 an engagement between the carbon block and the electrode in order that an arc may be started between them and for thereafter moving said frame to cause said arc to be maintained between the copper block and 80 the electrode.

8. In an arc lamp, an electrode, a movable frame carrying a block of carbon and a block of copper, said blocks being electrically connected, and means for actuating the frame 85 for causing an arc to be started from the carbon block and to be maintained between the electrode and the copper block.

9. In an arc lamp, an electrode comprising a movable frame and a block of carbon 90 and a block of copper carried thereby in fixed relation to the carbon block, a feeding mechanism, and a connection between said feeding mechanism and said frame.

10. In an arc lamp, an electrode comprising a member provided with a main arcing portion and an auxiliary arcing portion in fixed relation thereto, said portions being formed of different materials, a second electrode, and means for causing a movement 100 of said electrodes relative to each other to first start an arc between said auxiliary arcing portion and said second electrode and to then maintain said arc from said main portion.

11. In an arc lamp, an electrode comprising a frame carrying a copper arcing portion and a carbon arcing portion in fixed relation to the copper portion, a second electrode, means for causing an engagement between 110 said second electrode and said carbon arcing portion to start an arc and for thereafter causing a relative movement between said frame and said electrode to cause the arc to be maintained from the copper arcing portion.

12. In an arc lamp, an electrode, a movable frame carrying a block of carbon and a block of copper, and means for moving the frame to bring first the carbon and then the 120 copper into proximity to said electrode.

13. In an arc lamp, an electrode, a metal block, a second block, and means for first bringing the said second block and said electrode together to start an arc between them 125 and then moving said second block away from said electrode and said metal block toward said electrode whereby the arc will be caused to be maintained from said metal block.

14. In an arc lamp, a movable electrode having a main arcing portion formed of copper, and in fixed relation thereto, an auxiliary arcing portion formed of carbon.
- 5 15. In an arc lamp, a pivoted frame carrying a main arcing portion formed of copper, and an auxiliary arcing portion formed of carbon pivotally connected to said frame.
16. In an arc lamp, a frame oscillating 10 about an axis, and a carbon block connected thereto, the under surface of said block being cylindrical with respect to the axis about which the frame oscillates.
17. In an arc lamp, an electrode mounted 15 to oscillate about an axis, and a block of carbon carried thereby and mounted to turn about an axis located in a plane perpendicular to the axis about which the electrode oscillates.
- 20 18. In an arc lamp, a main electrode oscillating about an axis, and an auxiliary electrode carried by said main electrode and mounted to oscillate about an axis in a plane perpendicular to the axis about which the 25 main electrode oscillates.
19. In an arc lamp, an electrode comprising a movable frame and a metal arcing portion and a non-metal arcing portion carried thereby in fixed relation to each other, a 30 feeding mechanism, and a connection between said feeding mechanism and said frame.
20. In an arc lamp, an electrode, a non-metal arcing member, a metal arcing member, and means for moving said members suc- 35 cessively across the end of said electrode in the feeding operation of the lamp.
21. In an arc lamp, an electrode mounted to swing in two planes, a second electrode movable rectilinearly in one of these planes 40 into impact with the first electrode, said first electrode being formed with two contact surfaces, whereby when the electrodes are brought into engagement with each other at one point the swinging electrode is forced 45 about one of its axes to engage with the other electrode at a second point, and means for bringing the electrodes into engagement.
22. In an arc lamp, an electrode, a carbon block mounted to swing in two planes and 50 formed with two distinct contact surfaces, and means for bringing the arcing end of the electrode into engagement with the block, whereby said block is swung about one of its axes to engage with the electrode at a point 55 away from the arcing end thereof.
23. In an arc lamp, a pair of electrodes, one movable in two planes and the other in one of said planes, and means for causing the electrodes to be brought into contact, where- 60 by when they are brought together a relative movement takes place which causes the electrodes to engage at a second point remote from the first point of contact.

In witness whereof I have hereunto set my 65 hand this 11th day of March, 1904.

WILLIAM S. WEEDON.
